CUTTING OR DRILLING DEVICE

Charles E. Stoltz, Chicago, Ill., assignor to Goodman Manufacturing Company, Chicago, Ill., a corporation of Illinois

Application June 27, 1941, Serial No. 400,051

16 Claims. (Cl. 262—28)

This invention relates to improvements in cutting or drilling devices and more particularly relates to a new and improved drilling device particularly adapted for drilling relatively large holes in mines underground.

The present invention relates to a drilling device somewhat similar to that disclosed in a prior application Serial No. 379,218, filed jointly by me and Clem C. Austin on February 17, 1941, now Patent No. 2,292,098, but differs from said prior application in that the rotating parts of the drilling mechanism are protected and the drilling mechanism is adapted to be mounted on a post instead of a truck, and in that a different means is provided for guiding the cutter chain, which means also forms an enclosure for the cutter chain.

The principal objects of my invention are to provide a new and improved drilling device presenting a number of traveling cutting surfaces to the coal face and including a cutter chain adapted to make an endwise cut while being driven in a closed orbital path at the same time it is being rotatably driven, together with a novel form of guide means for the chain, enclosing all of the chain except the extreme forward cutting end thereof.

A more specific object of my invention is to provide a novel form of guide means for the cutter chain which also forms an enclosure for all except the forward cutting end thereof, which guide means is so arranged as to aid in removing the cuttings from the drill hole.

Other objects of my invention will appear from time to time as the following specification proceeds and with reference to the accompanying drawings wherein:

Figure 1 is a view in side elevation of a drilling mechanism constructed in accordance with my invention, showing the drilling mechanism cutting a hole in a mine wall;

Figure 2 is a rear end view of the device shown in Figure 1, and showing certain details of the post for supporting the drill;

Figure 3 is an enlarged fragmentary longitudinal sectional view of the device shown in Figure 1;

Figure 4 is a plan view of the device, drawn to substantially the same scale as Figure 3, with certain parts broken away and certain other parts shown in horizontal section;

Figure 5 is a transverse sectional view taken substantially along line 5—5 of Figure 3;

Figure 6 is a transverse sectional view taken substantially along line 6—6 of Figure 3;

Figure 7 is an enlarged detail view of the cutting element, with certain parts broken away and certain other parts shown in section;

Figure 8 is a detail view of the cutting element, drawn to a slightly smaller scale than Figure 7, showing the cutting element cutting in the mine wall and showing certain parts thereof in section;

Figure 9 is an enlarged detail view of the cutter chain, with certain parts shown in section;

Figure 10 is a transverse sectional view taken substantially along line 10—10 of Figure 9;

Figure 11 is a transverse sectional view taken through the front end of the cutting element in order to show certain details thereof; and

Figure 12 is a transverse sectional view of the cutting element, taken substantially along line 12—12 of Figure 7.

The embodiment of my invention illustrated in the drawings includes a drilling mechanism generally indicated by reference character 10, mounted on a post or jack 11, for vertical adjustment with respect thereto.

The post 11 is of a usual construction commonly used in mines for supporting a drill during cutting, and includes a collar 13 abutting the underside of a column 14 and threaded on a vertical shaft 15, for securely engaging laterally spaced engaging ends 16 and 17 of said post with the mine roof and bottom and for holding said column in position during the drilling operation. A sleeve 18 has a bracket 19 projecting laterally therefrom and forms an adjustable support for a thread bar 20 and a supporting

35 and guiding bar 21 for the drilling mechanism. Said sleeve is mounted on said column for vertical adjustment with respect thereto, and is vertically moved along said column by means of a ratchet device generally indicated by reference character 22 (see Figure 2). Said ratchet device may be of a usual type, such as is used in lifting jacks, and will not herein be shown or described in detail since it is no part of my present invention.

45 The thread bar 20 and guiding bar 21 are mounted in the bracket 19 at their rear ends and extend therefrom in parallel relation with respect to each other in a generally horizontal direction. Said supporting and guiding bar has an adjustable engaging end 24, adapted to be engaged with the mine wall by means of a threaded hand wheel 25. Said hand wheel has bearing engagement with the forward end of said supporting and guiding bar and is threaded on a rearwardly projecting portion of said engaging end

of said bar. A similar engaging member (not shown) is provided on the forward end of said thread bar, for engagement with the mine wall, for holding said feed bar in position in the mine wall.

The drilling mechanism is supported on the thread bar 20 and guide bar 21 by means of a frame 27 forming a housing for certain of the drive gearing for the drilling mechanism, and by means of a forwardly spaced depending support member 28 secured to a forwardly projecting portion 29 of said frame. Bottom housing pieces 30 and 31 are secured to the underside of said frame and said forwardly projecting portion of said frame, respectively. Said bottom housing piece 30, with the underside of said frame 27, forms a bearing support for a threaded sleeve 33, threaded on said thread bar; and said forwardly projecting portion 29, with said bottom housing piece 31, forms a support for a bearing sleeve 34, mounted in said forwardly projecting portion and forming a means for supporting said drilling mechanism for slidable movement along said thread bar. Similar bearing sleeves (not shown) spaced laterally from said sleeves 33 and 34 are mounted in the lower portion of said frame 27 and are held in engagement therewith by means of said bottom housing portions 30 and 31 respectively, and form bearings for the guide bar 21 for supporting said drilling mechanism for slidable movement along said guide bar.

A motor 35 is provided to move the drilling mechanism along the thread bar 20 and support bar 21 at a relatively slow feeding speed. Said motor is mounted at one of its ends on an upwardly projecting rear wall 38 of the frame 27, and projects rearwardly therefrom. A pinion 36 is keyed on an armature shaft 37 of said motor and meshes with and drives a spur gear 39, freely mounted on the threaded sleeve 33. Said spur gear is connected with said sleeve, for rotatably driving said sleeve at a frictionally controlled speed by means of a friction disk 40 mounted on a flange 41 of a driven member 43, feathered on the outside of the threaded sleeve 33. Said friction disk is engaged with one side face of said gear by a compression spring 44, interposed between a flanged portion 45 of said sleeve and the flange 41 of the driven member 43.

Referring now in particular to certain details of the drilling mechanism, the cutting mechanism for drilling includes a cutter chain 47 guided for movement within and beyond the forward end of an elongated casing 49. Said casing is rotatably mounted on the frame 27 and the support member 28 on ball bearings 50, 51, and 52 in a manner which will herein more clearly appear as this specification proceeds (see Figures 3 and 4).

The elongated casing 49 includes a tube 53 threaded within and projecting forwardly from a forward housing portion 54 of said casing. Said forward portion of said casing is mounted within the ball bearing 52, which in turn is mounted in the support member 28. A rear housing portion 55 of said casing is secured to and projects rearwardly of said forward portion and is provided with a rearwardly projecting cylindrical portion 56, mounted on the ball bearings 50 and 51.

The means for holding said tube for rotation with said housing portion of said casing includes a key 57 engaging a keyway 58 in said housing. It also includes a retaining collar 59, threaded on said tube and abutting the forward end of the

forward housing portion 54, and locked for rotation with said housing by means of a locking screw 60, threaded within said collar and engaging a suitable recessed portion of said forward housing (see Figure 3). Said holding means also includes a collar 61 threaded on the inner end of said tube and abutting an inner shouldered portion 62 of said forward housing portion and locked in engagement with said housing portion by means of a locking screw 63.

The forward housing portion 54 is provided with a rearwardly projecting portion 64, which projects within the rear housing portion 55, and which has a pair of ball bearings 65, 65 mounted therein and forming bearings for a shaft 66. A sprocket 67, keyed on said shaft, meshes with the cutter chain 47 for driving said cutter chain within the tube 53 and beyond the forward end thereof.

Said sprocket is of a larger diameter than the inside diameter of said tube, and guide members 94, 94 are provided to restrict the path of travel of the chain so it will enter and pass through said tube. Said guide members will hereinafter be more clearly described as this specification proceeds. This construction enables the chain to be efficiently driven by a sprocket of a relatively large number of teeth without increasing the diameter of the tube 53, through which said chain passes, to a point where it would be impractical to cut clearance therefor, and still maintain the hole to the required size for the insertion of a blasting cartridge.

The rear housing portion 55 is secured to an annular shouldered portion of said forward housing portion by means of cap screws 68, 68 and forms a housing for a bevel pinion 69, keyed on the shaft 66 outside of the rearwardly projecting portion 64 of the forward housing portion 54, and also forms a housing for a bevel gear 70, meshed with said bevel pinion. Said bevel gear, as herein shown, is provided with an integrally formed rearwardly projecting shaft 71, extending through the ball bearings 50 and 51 and forming a support for said ball bearings, for rotatably mounting said rear housing portion on the upwardly projecting wall 38 of the frame 27. Said shaft extends through said rear wall and is secured to and held from rotation with respect to said frame by means of nuts 72 and 73, threaded on said shaft and engaging opposite sides of said rear wall.

The cylindrical portion 56 of said rear housing portion has a spur gear 74 keyed on the outside thereof and meshed with and driven from the armature pinion 36, for rotatably driving the casing 49 about its longitudinal axis and for driving the cutter chain within said elongated casing and beyond the forward end thereof by the walking action of the bevel pinion 69 around the stationary bevel gear 70.

The cutter chain 47 is herein shown as being an ordinary link type roller chain with bit holding attachments 75, 75, connecting the links of said chain together and alternately extending laterally from opposite sides of said chain (see Figures 9 and 10). Each laterally extending portion of each bit holding attachment is provided with a recess 76 for receiving a cutter bit 77. Each of said bits is held in position in its respective recess by means of a locking pin 79 extending longitudinally through said attachment and recess and engaging a recessed portion 80 of said bit. As herein shown, said bits are provided with two cutting points so that when one

point is dulled, the bit may be reversed and the other point used for cutting.

The cutter chain 47 passes from the sprocket 67 through the tube 53 to and around a direction changing device at the forward end of said tube, herein shown as being an idler roller 83 mounted in a forked open forward portion of said tube, on a shaft 84. Said idler roller 83 is mounted on a bearing 85, which is mounted on the shaft 84. Said shaft is mounted at its ends in opposite furcations of the forked forward end of the tube 53, which furcations are herein shown as being reinforced by reinforcing plates 86, 86 extending along opposite sides thereof. The outer diameter of said idler roller is such that the bits 71, 71 will subscribe an arc of a diameter sufficient to cause said bits to cut clearance for said tube as they make an endwise cut in the mine wall, to permit said tube to follow said chain within the hole which is being cut.

The means for guiding the cutter chain 47 within said tube includes a plate 93, herein shown as extending along the central portion of said tube and as being adapted to have the outgoing and return runs of said cutter chain move along opposite sides thereof. Said chain is held in sliding engagement with said plate by means of guide members 94, 94, mounted within said tube on opposite sides of said plate and engaging the outsides of the bit holding attachments 75, 75. The forward and rear ends of said guide members are curved outwardly to engage said cutter chain and to restrict its path so it will readily move through said tube.

Openings 95, 95 are provided along said tube at spaced intervals, to permit the cuttings brought rearwardly by the cutter chain 47 to be discharged therethrough during rotation of said tube. Likewise, a plurality of openings 96, 96 are provided in the housing portion 55, for the discharge of cuttings therefrom.

A spiral conveying fin 97 extending along the outside of said tube from the forward to rear end thereof, is provided to progress the cuttings rearwardly along the hole which is being drilled, upon rotation of said tube, and to prevent said cuttings from fouling said tube during the cutting operation.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a drilling device, a bit carrying cutter chain, an elongated casing open at its forward end and forming a guide means for said cutter chain, means for rotatably driving said casing about its longitudinal axis, a drive sprocket of a larger diameter than the inside diameter of said casing, for driving said cutter chain, and means for guiding said cutter chain from said drive sprocket into said casing and for movement within said casing and beyond the forward end thereof, for cutting a round hole upon rotatable movement of said casing about its longitudinal axis.

2. In a drilling device, a bit carrying cutter chain, an elongated casing open at its forward end and forming a guide means for said cutter chain, and means for rotatably driving said casing about its

longitudinal axis, a drive sprocket of a larger diameter than the inside diameter of said casing, for driving said cutter chain, means disposed within said casing for guiding said cutter chain from said drive sprocket into said casing and for movement within said casing, and direction changing means at the open forward portion of said casing, for changing the direction of said cutter chain and for guiding said cutter chain for cutting a round hole beyond the forward end of said casing upon rotatable movement of said casing about a longitudinal axis.

3. In a drilling device including an elongated casing, a bit carrying cutter chain, a sprocket of larger diameter than the inside diameter of said casing, for driving said cutter chain within said casing, means for guiding said cutter chain for movement within said casing including a member extending along said casing and dividing said casing into two parts along which the outgoing and return runs of said chain travel and other means for engaging said chain with said dividing member, to cause it to travel within said casing.

4. In a drilling device including an elongated casing, a bit carrying cutter chain and means for guiding said cutter chain for movement within said casing including a member extending along said casing and dividing said casing into two parts along which the outgoing and return runs of said chain travel, a sprocket of a larger diameter than the inside diameter of said casing, for driving said cutter chain about said dividing member, and guide strips spaced from opposite sides of said member and extending parallel thereto and engaging the outsides of said cutter chain, for guiding said cutter chain within said casing and maintaining the outgoing and return runs of said cutter chain in engagement with opposite sides of said member.

5. In a drilling device, an elongated casing, means for rotatably driving said casing about its longitudinal axis, a bit carrying cutter chain, a cutter chain sprocket of larger diameter than the inside diameter of said casing, for driving said cutter chain within said casing and beyond the forward end thereof, and guide means for said cutter chain including a member extending along said casing and dividing said casing into two parts, guide strips spaced from opposite sides of said member and extending along each of said parts and engaging the outsides of said cutter chain, for maintaining the outer and return runs of said cutter chain in engagement with opposite sides of said member, during passage of said chain through said casing, and a rotatable direction changing member at the forward end of said casing for guiding said cutter chain to cut a round hole of a larger diameter than said casing, upon rotatable movement of said casing about said longitudinal axis.

6. In a drilling apparatus, a cutter chain, a chain guiding member for guiding said chain in a closed orbital path, power operated means for rotating said chain guiding member about its longitudinal axis and for driving said chain orbitally about said guiding member including a motor and a geared drive connection from said motor to said chain guiding member, and another geared drive connection from said motor, for feeding said chain guiding member in an endwise direction during rotation of said chain guiding member and movement of said cutter chain about said chain guiding member.

7. In a drilling device, an elongated casing open

at its ends, a bit carrying cutter chain, means for guiding said cutter chain for movement within said casing, direction changing means at the open forward portion of said casing, for changing the direction of said cutter chain and for guiding said cutter chain to cut beyond the forward end of said casing, means for rotatably driving said casing and for simultaneously driving said cutter chain within said casing for causing said cutter chain to cut a round hole, and openings within said casing to permit the discharge of the cuttings therefrom.

8. In a drilling device, a bit carrying cutter chain, an elongated casing open at its ends, means for guiding said cutter chain for movement within said casing, direction changing means at the open forward portion of said casing, for changing the direction of said cutter chain and for guiding said cutter chain beyond the forward end of said casing, means for rotatably driving said casing and for simultaneously driving said cutter chain within said casing, means for feeding said casing in an endwise direction in a mine wall for causing said cutter chain to cut a round hole, upon rotation of said casing, and means on the outside of said casing for propelling the cuttings rearwardly along said casing, upon rotation thereof.

9. In a drilling device, a bit carrying cutter chain, an elongated casing open at its ends, means for guiding said cutter chain for movement within said casing, direction changing means at the open forward portion of said casing, for changing the direction of said cutter chain and for guiding said cutter chain beyond the forward end of said casing, means for rotatably driving said casing and for simultaneously driving said cutter chain within said casing, means for feeding said casing in an endwise direction in a mine wall, for causing said cutter chain to cut a round hole, upon rotation of said casing, and means for propelling the cuttings rearwardly along said casing, upon rotation thereof, including a spiral conveyer extending along the outside of said casing.

10. In a drilling device, a bit carrying cutter chain, an elongated casing open at its ends, means for guiding said cutter chain for movement within said casing, direction changing means at the open forward portion of said casing, for changing the direction of said cutter chain and for guiding said cutter chain to cut beyond the forward end of said casing, means for rotatably driving said casing and for simultaneously driving said cutter chain within said casing, means for feeding said casing in an endwise direction in a mine wall for causing said cutter chain to cut a round hole upon rotation of said casing, openings in said casing to permit the discharge of the cuttings therefrom, and means on the outside of said casing, for propelling the cuttings rearwardly therealong.

11. A drilling device including an elongated casing, a bit carrying cutter chain guided for movement within said casing and beyond the forward and rear ends thereof, a sprocket of a larger diameter than the inside diameter of said casing, for driving said cutter chain, and means for guiding said cutter chain for movement within said casing including a rotatable direction changing member at the forward end of said casing, a plate extending along said casing intermediate the side walls thereof, and means mounted within said casing on the opposite sides of said plate and engaging the outsides of said cutter chain and maintaining the outer and return runs of said

cutter chain in engagement with opposite sides of said plate, during passage of said chain through said casing.

12. A drilling device including an elongated casing, a bit carrying cutter chain guided for movement within said casing and beyond the forward and rear ends thereof, and means for guiding said cutter chain for movement within said casing including a rotatable direction changing member at the forward end of said casing, a plate extending along said casing intermediate the side walls thereof, means mounted within said casing on the opposite sides of said plate and engaging the outsides of said cutter chain and maintaining the outer and return runs of said cutter chain in engagement with opposite sides of said plate, during passage of said chain through said casing, and spaced openings in said casing to permit the discharge of cuttings therefrom.

13. A drilling device including an elongated casing, a bit carrying cutter chain guided for movement within said casing and beyond the forward and rear ends thereof, and means for guiding said cutter chain for movement within said casing including a rotatable direction changing member at the forward end of said casing, a plate extending along said casing intermediate the side walls thereof, means mounted within said casing on the opposite sides of said plate and engaging the outsides of said cutter chain and maintaining the outer and return runs of said cutter chain in engagement with opposite sides of said plate, during passage of said chain through said casing, and spaced openings in said casing to permit the discharge of cuttings therefrom.

14. A drilling device including an elongated casing, a bit carrying cutter chain guided for movement within said casing and beyond the forward and rear ends thereof, and means for guiding said cutter chain for movement within said casing including a rotatable direction changing member at the forward end of said casing, a plate extending along said casing intermediate the side walls thereof, means mounted within said casing on the opposite sides of said plate and engaging the outsides of said cutter chain and maintaining the outer and return runs of said cutter chain in engagement with opposite sides of said plate, during passage of said chain through said casing, and a spiral on the outside of said casing, for progressing the cuttings rearwardly therealong.

15. A drilling device including an elongated casing, a bit carrying cutter chain guided for movement within said casing and beyond the forward and rear ends thereof, a cutter chain drive sprocket of a larger diameter than the inside diameter of said casing, for driving said cutter chain, means for guiding said cutter chain from said sprocket into said casing and for movement within said casing including a rotatable direction changing member at the forward end of said casing, a plate extending along said casing intermediate the side walls thereof, means mounted within said casing on the opposite sides of said plate and engaging the outsides of said cutter chain and maintaining the outer and return runs of said cutter chain in engagement with opposite sides of said plate, during passage of said chain through said casing, spaced openings in said casing to permit the discharge of cuttings therefrom, and a spiral on the outside of said casing, for progressing the cuttings rearwardly therealong.

16. A drilling device including an elongated casing, a bit carrying cutter chain guided for movement within said casing and beyond the forward and rear ends thereof, a cutter chain drive sprocket of a larger diameter than the inside diameter of said casing, for driving said cutter chain, means for guiding said cutter chain from said sprocket into said casing and for movement within said casing including a rotatable direction changing member at the forward end of said casing, a plate extending along said casing intermediate the side walls thereof, means mounted within said casing on the opposite sides of said plate and engaging the outsides of said cutter chain and maintaining the outer and return runs of said cutter chain in engagement with opposite sides of said plate, during passage of said chain through said casing, means disposed rearwardly of said casing for rotatably driving said casing and driving said cutter chain drive

sprocket, and means for feeding said casing in a longitudinal direction, for causing said cutter chain to cut a circular hole in a mine wall of a larger diameter than said casing.

16. A drilling device including an elongated casing, a bit carrying cutter chain guided for movement within said casing and beyond the forward and rear ends thereof, and means for guiding said cutter chain for movement within said casing including a rotatable direction changing member at the forward end of said casing, a plate extending along said casing intermediate the side walls thereof, means mounted within said casing on the opposite sides of said plate and engaging the outsides of said cutter chain and maintaining

the outer and return runs of said cutter chain in engagement with opposite sides of said plate, during passage of said chain through said casing, means for rotatably driving said casing and driving said cutter chain therethrough, means for feeding said casing in a longitudinal direction, for causing said cutter chain to cut a circular hole in a mine wall, spaced openings in said casing to permit said cutter chain to discharge the cuttings therethrough, and a spiral conveyer vane on the outside of said casing, for progressing the cuttings rearwardly therealong, upon rotation of said casing.

15

CHARLES E. STOLTZ.
